UNITED STATES PATENT OFFICE.

HUGH C. CARROLL, OF MCKEESPORT, PENNSYLVANIA.

WALL AND BLOCK FOR FORMING THE SAME.

Application filed October 28, 1922. Serial No. 597,535.

To all whom it may concern:

Be it known that I, HUGH C. CARROLL, a citizen of the United States, residing at McKeesport, in the county of Allegheny and State of Pennsylvania, have invented certain new and useful Improvements in Walls and Blocks for Forming the Same, of which the following is a specification, reference being had therein to the accompanying drawings.

This invention relates to walls and blocks for forming the same and it has for its object to provide a concrete block constructed in such manner that it may be laid up as easily and with no more skill than is required in laying ordinary concrete blocks, but wherein the finished wall will present the appearance of a rubble or cobble-stone wall and wherein the joints between the several blocks will be so concealed as to be invisible.

Further objects and advantages of the invention will be set forth in the detailed description which follows.

In the accompanying drawings:

Fig. 1 is a face view of a fragment of a wall constructed in accordance with the invention;

Fig. 2 is a front elevation of a block made in imitation of cobble-stone;

Fig. 3 is a face view of a block made in imitation of random rubble work;

Fig. 4 is a horizontal sectional view through a part of the wall;

Fig. 5 is an end elevation of one of the blocks;

Fig. 6 is a vertical sectional view through a part of a wall provided with an interior air space; and

Fig. 7 is a detail sectional view showing the block used to face a wooden building.

Like numerals designate corresponding parts throughout the several figures of the drawings.

Broadly speaking the invention consists of a concrete block comprising a front portion and a rear portion integral with each other but with the front portion offset with respect to the rear portion so that one side and one end of the front portion projects beyond the confines of the rear portion, while the other side and end lies inwardly of the confines of said rear portion. The faces of the outer portion of the block are provided with a series of irregular grooves or channels in imitation of the division line between cobble-stone or rubble work and said offset

outer portions of the block are irregularly shaped but conform to the adjacent or meeting edges of adjacent blocks and the blocks are so arranged that while they may be laid in staggered relation to each other in the usual way in a wall, their meeting edges will exactly match and when a heavy beaded pointing is applied to the grooves or channels in the faces of the blocks and to the channels along the meeting edges between said blocks, the joint between the meeting edges is so concealed as not to be visible to an ordinary observer. Thus the effect of expensive stone walls such as usually require the services of high priced artisans is secured through the medium of the employment of concrete blocks.

Referring now more particularly to the drawings, 5 designates the inner portion and 6 the outer portion of a concrete block constructed in accordance with the invention. The edges of the inner portion are straight and said inner portion is rectangular in formation so that when laid up in the wall these inner portions rest upon and engage one another much after the manner of an ordinary concrete block. The outer portions of the block are offset from the inner portions to leave a projecting side 7, a projecting end 8, a recessed side 9 and a recessed end 10, the recessed end 10 of one block receiving the corresponding projections upon the projecting end 8 of an adjacent block, and the recessed side 9 receiving the projecting portions of the two blocks next below, it being understood that these blocks are laid in staggered relation in a wall to break joints in the usual way. A series of irregular grooves 11, 11^a divides the blocks into irregular spaces in imitation of cobble-stone or rubble, as the case may be, it being understood that these grooves are formed in the moulding or casting of the stone and that the faces representing the faces of the cobble-stone or rubble will be suitably shaped in the moulding as by making it in relief or intaglio as the case may be, to produce the desired effect. After the wall has been laid up, a beaded pointing 12, usually of keen white cement, though it may be of any color or any suitable material, is laid in the grooves 11, 11^a and that pointing that is laid in the grooves at the meeting edges of the blocks is designedly spread enough to cover the joints between the blocks and conceal them. To

this end the grooves at the meeting edges of the blocks are so formed as to lie complementally in the adjacent blocks and the finished beaded pointing completely overlies the joint. To aid in forming an interlock between the several blocks, I preferably vertically groove the ends of the inner portion 5 of the block, as indicated at 5^a, and fill this space with cement mortar, indicated 10 at 13.

From the foregoing it will be observed that the joints are broken between the several inner portions of the blocks. In other words these inner portions are laid up in 15 staggered relation in the usual way. But in addition to that, the joints between the outer portions of the blocks are staggered with relation to the joints between the inner portions of the block, this being brought 20 about by offsetting the outer portions with respect to the inner portions in the manner indicated. This offsetting of the outer portions with respect to the inner portions serves a further useful purpose in that the 25 projecting surfaces 5^b and 5^c of the inner portions of the block, left by reason of the offsetting of the outer portions, act as a guide or gauge in accurately positioning the blocks with respect to each other in the 30 laying of the wall. In other words, in order to accurately bring the projecting end of the outer portion of one block into engagement with the indented end of the projecting portion of another block, it is only necessary to lay the inner surface of the outer portion of the one block against the 35 projecting surface 5^b, for example, and then slip the projecting end into the recessed portion of the adjacent block.

40 In the form of the invention illustrated in Fig. 6 I have illustrated a wall comprising an inner portion 15 made of ordinary concrete blocks and an outer portion 16 faced

with blocks made in accordance with the present invention, these two portions being 45 tied together by galvanized wall ties 16^a having bent ends which enter recesses formed in the tops of the blocks and which wall ties are embedded in the mortar joints 50 between the blocks.

In the form of the invention illustrated in Fig. 7 I have illustrated the improved blocks of the present invention utilized to face a wooden building. In this case the facing blocks 17 are tied to the building by 55 ties 18 having downturned inner and outer ends, the outer ends being embedded in the mortar joints of the blocks and entering recesses formed in the tops of the blocks and the inner ends engaging in staples 19 driven 60 into the wooden building.

It is to be understood that the invention is not limited to the precise construction set forth but that it includes within its purview whatever changes fairly come within either 65 the terms or the spirit of the appended claim.

Having described my invention what I claim is:

A block of the character described comprising an inner portion and an outer portion, the inner portion having its edges straight and rectangular and the outer portion having its face irregularly channeled in imitation of the joints between a plurality of irregularly formed stone, the edges of the outer portion of the block being irregularly shaped and matching the contacting portions of adjacent blocks and producing joints between adjacent blocks corresponding in appearance to the imitation joints formed on the face of the block.

In testimony whereof I hereunto affix my signature.

HUGH C. CARROLL.
